WINDOW-SASH LOCK.

1,043,842.

Specification of Letters Patent.

Patented Nov. 12, 1912.

Application filed February 24, 1912. Serial No. 679,661.

To all whom it may concern:

Be it known that I, NATHANIEL KAHN, a citizen of the United States, and residing at New York, in the county of New York 5 and State of New York, have invented certain new and useful Improvements in Window-Sash Locks, of which the following is a specification, such as will enable those skilled in the art to which it appertains to 10 make and use the same.

This invention relates to window sash locks, and the object thereof is to provide an improved device of this class which is independent of the sash or window frame, but 15 which may be quickly and easily applied so as to lock both sashes in a closed position whenever desired.

The invention is fully disclosed in the following specification of which the accompanying drawing forms a part in which the 20 separate parts of my invention are designated by suitable reference characters in each of the views, and in which:—

Figure 1 is a perspective view showing 25 part of a window frame and part of both sashes, and showing my improved sash lock applied and;—Fig. 2 a section on the line 2—2 of Fig. 1.

In the drawing forming part of this specification I have shown at *a* a part of one side of a window frame, and I have also shown at *b* a part of the upper sash, and at *c* a part of the lower sash, and the frame *a* is provided with the usual beads or strips *d* and 35 *e* between which the lower sash is mounted, the outer bead or strip *d* also serving as one of the guides for the upper sash.

My improved sash lock comprises a back plate *f* and a front plate *g* slidably mounted one upon the other, and the back plate *f* is provided at its top and bottom edges with longitudinal keepers *f*¹ in which the front plate *g* is longitudinally movable. The front plate *g* is provided at its outer end 40 with a right angled member *g*² having sharp pointed teeth *g*³ on its outer surface, and the back plate *f* is provided at its front end with a similar right angled member *f*² having sharp pointed teeth *f*³ on its inner surface. The front plate *g* is also provided in 45 its inner end portion with a longitudinal slot *g*⁴, and passed through the back plate *f* and through the slot *g*⁴ is a screw or bolt *h*, and mounted on said bolt in front of the 50 plate *g* is an arm *i* which ranges forwardly

and longitudinally of said plate *g*, and through which is passed a threaded screw or bolt *j* which also passes through a curved slot *g*⁵ in the plate *g*, and the screw or bolt *j* is provided with a thumb nut *k*, and mounted on said screw or bolt, between the plate *g* and the arm *i*, is a lever *m* which is pivoted to the plate *g* at *m*² and which ranges cross-wise of said plate and the slot *g*⁵, and is provided with a handle portion *m*³, and the slot *g*⁵ is concentric to the pivoted point of the lever *m*. 60 65

The screw or bolt *h* is preferably provided with two washers *n* and *n*², as shown, and it will be observed that the front plate *g* is longer than the back plate *f*, and is provided with a projecting end portion *g*⁶ in which the slot *g*⁵ is formed, and on which the lever *m* is mounted, and the operation will be readily understood from the foregoing description, when taken in connection with the accompanying drawing, and the following statement thereof. 70 75

In order to apply this device the sashes are closed, as shown in Fig. 1, and the lock is 80 placed in position over the bottom sash, as is also shown, with the right angled member *g*² of the plate *g* between one side of the top sash and the adjacent bead or strip *d*, and the right angled member *f*² of the plate *f* 85 fitting against the inner side of the bead or strip *e*, and with the parts adjusted to this position the lever *m* is moved in the direction of the arrow *x*. This movement of said lever forces the plate *f* forwardly, and the plate *g* backwardly, and forces the teeth *f*³ 90 into the bead or strip *e* and the teeth *g*³ into the side of the top sash, and the sash lock is securely held in position, and the sashes *b* and *c* are locked against movement. It will 95 be understood that in order to manipulate the lever *m* the nut *k* must be loosened and when said lever is in operative position, as above described the nut *k* must be tightened; it will also be understood that in order to adjust the plates *g* and *f* into the desired position for use, the nut *k* must also be loosened. 100

My improved sash lock may be made of any desired dimensions, and by reason of the possible adjustment of the plates *f* and *g* as 105 above described the said sash lock may be applied to windows, or window sashes of varying transverse dimensions; and changes in and modifications of the construction herein described, may be made, within the 110

scope of the appended claim, without departing from the spirit of my invention or sacrificing its advantages.

Having fully described my invention what 5 I claim as new and desire to secure by Letters Patent is:—

A sash lock comprising a back plate and a front plate movable longitudinally thereon, said plates being provided at their corresponding outer ends with right angled members which project in the same direction, and one of which is provided on its outer and the other on its inner surface with teeth, the front plate being also provided with a central longitudinal slot and in the inner end 10 15

portion thereof with a curved slot, a lever pivoted to the front end portion of the front plate and ranging transversely of the curved slot, and a bolt passed through said curved slot and through said lever and through the 20 free end of said arm.

In testimony that I claim the foregoing as my invention I have signed my name in presence of the subscribing witnesses this 23rd day of February, 1912.

NATHANIEL KAHN.
